(57) **CLAIM**

The ornamental design for an electrosurgical handpiece, substantially as shown and described.

DESCRIPTION

FIG. 1 is a side elevational view of an electrosurgical handpiece showing our new design;

FIG. 2 is a top plan view thereof;

FIG. 3 is a front elevational view thereof;

FIG. 4 is a rear elevational view thereof;

FIG. 5 is a side elevational view of a second embodiment of an electrosurgical handpiece showing our new design;

FIG. 6 is a top plan view thereof, with the front and rear elevational views being the same as that shown in FIGS. 3 and 4;

FIG. 7 is a side elevational view of a third embodiment of an electrosurgical handpiece showing our new design; and, FIG. 8 is a top plan view thereof, with the front and rear elevational views being the same as that shown in FIGS. 3 and 4.

The broken lines showing in FIGS. 1, 2, 5, 6, 7 and 8 of the electrode and electrical cable are for illustrative purposes only and forms no part of the claimed design.
